ISAAC GAUSE, OF NATIONAL SOLDIERS' HOME, VIRGINIA.

SEPARABLE BUTTON.

1,149,124.

Specification of Letters Patent. Patented Aug. 3, 1915.

Application filed March 26, 1915. Serial No. 17,236.

To all whom it may concern:

Be it known that I, ISAAC GAUSE, a citizen of the United States, residing at National Soldiers' Home, in the county of Elizabeth 5 City and State of Virginia, have invented certain new and useful Improvements in Separable Buttons; and I do hereby declare the following to be a full, clear, and exact description of the invention, such as will 10 enable others skilled in the art to which it appertains to make and use the same.

This invention relates to separable buttons of that class having a sliding bar or latch, and the object of the same is especially 15 to improve the form of the latch so that when engaged with the eye of the post it clamps the latter to prevent a movement of the latch which would permit its tongue to disengage said eye, and when purposely dis- 20 placed from the hollow head. This and other objects are accomplished by constructing the separable button in the manner hereinafter described and as shown in the accompanying drawings wherein:

25 Figure 1 is a sectional view through all parts of the button assembled; Figs. 2, 3, 4 and 5 are perspective details of the parts of the hollow head or female member; Figs. 6, 7 and 8 are perspective details of different 30 forms of the male member including the solid head; and Fig. 9 is an enlarged plan view of the latch.

While the detail construction of the parts of this separable button is not important, excepting as they co-act with the improved latch described at length below, I have herewith illustrated what may be considered a practical construction of each although I do not wish to be limited in this respect. I 35 have shown the female member with a hollow head because it must have a transverse chamber in which the latch reciprocates, the chamber connecting with a hollow sleeve into which is passed the post of the male 40 member; and I have described the latter as including a solid head carried by the outer end of said post, because this head does not have to be hollow. I have illustrated said heads as of different size, as they will probably be constructed when the device is used 45 for a cuff button or in some forms of collar buttons, but the size of parts and their materials and ornamentation are matters of no importance, and it is quite obvious that the 50 button may be used wherever it is desired.

The hollow head comprises an outer plate

1 having an annular inturned flange 2 notched at one side as at 3; an inner plate 4 having a peripheral flange 5 capable of being snapped into engagement with said flange 2 and itself notched at 6 to register with the notch 3, the plate 4 being slotted as at 7; and a washer 8 of a size to stand between these plates and having a central slot 9.

In Fig. 5 is shown a tubular sleeve 10 notched out transversely at its outer end at 11 to produce two side tongues 12. These various parts are shown assembled in Fig. 1, the body of the sleeve 10 being passed 15 through the slot 7 in the inner plate 4, its tongues 12 curled over tongues 13 which may well be formed at the ends of the slot 9, and its notch standing in alinement with the two notches 6 and 3 of the outer and inner plates, which notches are caused to register with each other when the flanges 2 and 5 of these plates are snapped into engagement with each other. The washer may well be soldered or otherwise secured as at 14 to the 20 inner face of the outer plate. The parts thus far described constitute one member of this separable button with the exception of the latch.

The other member is variously shown in 25 Figs. 6, 7 and 8. It comprises a base plate 20 and a post 21 rising therefrom and having an eye 22 through its outer end. This eye may easily be formed if this post is of 30 wire as seen in Fig. 6, in which case the ends of the wire will be bent out and secured as by soldering at 23 to the inner face of the plate 20; the same description will apply if the post is made of strap metal as indicated 35 in Fig. 7; or the post may be a solid projection 25 secured at its base to or extending 40 integrally from the plate 20 as seen in Fig. 8, and pierced near its outer end with a transverse eye 26. In this or a similar manner is constructed the male member of the 45 separable button.

The latch best seen in Fig. 9 is by preference made of a single piece of spring wire. Beginning at the center of its length, it is 50 bent on itself as at 30, carried then outward 55 in two parallel contiguous members constituting a tongue 31, said members then looped or bent away from each other as at 32, and carried along past the sides of the tongue in two jaws 33 which are somewhat 60 longer than the tongue itself. At their inner ends these jaws are bent back upon 65

themselves as at 34, and carried again outward as at 35, then deflected toward each other to form shoulders which contact with the loops 32 at the points 36 which I will 5 call fulcrums; and beyond these shoulders the wires are carried along parallel lines into arms 37 which terminate at their ends (which are the extremities of the wire) in eyes or buttons constituting heads 38. It 10 will be seen that the tongue is made of two stretches preferably lying in contact with each other, and each jaw 33 also has a stretch 35 outside of it and nearly or quite in contact therewith; but I consider it important that the outer stretches touch the 15 loops 32 at the fulcrum points 36, whereas the arms 37 do not touch each other. This latch is shown in Fig. 1 as located between the washer 8 and the inner plate 4, its arms 20 passing through the registering notches 3 and 6, one of which I have indicated in dotted lines in Fig. 9; and it is obvious that the entire latch is capable of longitudinal movement according to the length of the 25 arms 37, the heads 38 limiting its inward movement by striking the flange 7 and the shoulders formed by the fulcrums limiting its outward movement.

In the use of this button, the heads 38 are 30 pressed toward each other as indicated in dotted lines in Fig. 9 so that the arms 37 come out of contact with the end walls of the notch 6, and the entire latch is drawn out which would be toward the right in that 35 view. The tubular shank or sleeve 10 is then passed through the articles to be buttoned, and the male member of the button is brought into use and its post inserted into the outer end of this sleeve. When the 40 eye 22 or 26 in this post comes into position opposite the bend 30 of the tongue 31, the operator grasps the heads 38 and pinches them together slightly, and then pushes the entire latch inward so that the tongue 31 is 45 passed completely through the eye. When now he releases pressure on said heads, the two jaws move from the dotted position in Fig. 9 inward until they clamp against the outer sides or edges of the post opposite its 50 eye, such clamping action being the result of the natural spring tendency of the latch. Therefore the latter cannot become accidentally displaced and at this time the heads 38 stand quite close to the flanges of the 55 hollow button head so that it is extremely unlikely that any garment will catch therein—in fact said flanges could incline inward to such an extent that the heads 38 would be completely hidden. To separate the 60 parts of this button the operation is reversed. When the heads 38 are grasped and pressed toward each other, the sides of the wire latch rock over the fulcrums 36 so that their jaws spread apart as shown in dotted 65 lines in Fig. 9 and release their grip on the

post, while their arms 37 move inward to the dotted positions and release their contact with the ends of the notch 6. Then the operator can draw the latch outward within the hollow head, and its tongue disengages the eye of the post, so that the other member of the button can be withdrawn. Attention is directed to the fact that this spring latch when in place has four points of contact to prevent its becoming displaced—two of them where it touches the sides of the post and the other two where it touches the ends of the notch. When not in use and when the post is entirely removed, the latch cannot become displaced because its arms contact with the ends of the notch 6; and even if they did not, the shoulders outside the fulcrum points 36 are too large to pass through this notch.

In conclusion, I desire to repeat and emphasize the fact that the accompanying drawings are intended to illustrate only one of many constructions which might be adopted for the female member and only three for the male member; and, as above suggested, the latch is also susceptible of considerable modification, especially with respect to its arms 37 and heads 38. Therefore I do not wish to be limited in these respects.

What I claim is:

1. A member having a post projecting from it and provided near its outer end with a transverse eye; combined with a second member, and a latch slidably mounted there-in and including a tongue adapted to be projected through said eye, two spring jaws adapted to clamp the sides of said post when the tongue stands within the eye; and a handle projecting from this member.

2. A member having a post projecting from it and provided near its outer end with a transverse eye; combined with a second member, and a latch slidably mounted there-in and including a tongue adapted to be projected through said eye, two spring jaws adapted to normally clamp the sides of said post, and a pair of spaced arms connected with and projecting from said jaws out of said member and adapted when pressed toward each other to separate the jaws, for the purpose set forth.

3. In a separable button, the combination with a male member having a post provided near its outer end with a transverse eye; of a female member including a hollow head having a slot in its inner plate and a notch in its edge opposite one side of the slot, and a latch slidably mounted within said head and consisting of a tongue adapted to be projected through said eye, spring jaws at opposite sides of said tongue, arms projecting out of said notch and adapted normally to engage the ends thereof, and heads at the outer ends of said arms.

4. In a separable button, the combination with a male member having a post provided near its outer end with a transverse eye; of a female member including a hollow head having a slot in its inner plate and a notch in its edge opposite one side of the slot, and a latch slidably mounted within said head and consisting of a spring wire bent into a tongue adapted to be projected through said eye, looped outward from said tongue and bent into jaws extending alongside and beyond the tongue and adapted normally to grip the post, then carried back outside said jaws and formed into shoulders resting on said loops, and then carried farther outward in arms projecting through said notch and normally contacting with its ends.
5. In a separable button, the combination with a male member having a post provided near its outer end with a transverse eye; of a female member including a hollow head having a slot in its inner plate and a notch in its edge opposite one side of the slot, and a latch slidably mounted within said head and consisting of a spring wire bent into a tongue adapted to be projected through said eye, looped outward from said tongue and bent into jaws extending alongside and beyond the tongue and adapted normally to grip the post, then carried back outside said jaws and formed into shoulders resting on said loops and wider than the notch, then
- continued in parallel arms extending out said notch and normally contacting with its ends, and finally formed into heads on the 35 exterior of said hollow button head.
6. In a separable button, the combination with the male member including a head, and a post rising therefrom and having a transverse eye near its outer end; of the female member including a hollow head comprising outer and inner plates connected around their peripheries and having a notch in the edge, and a washer between said plates, the inner plate and washer having registering 40 slots, a tubular sleeve having its inner end passing through said slots and provided with tongues engaging said washer and its body notched out between said tongues on a line with the peripheral notch in the head; and a latch slidably mounted within said hollow head and including a tongue adapted to be projected through the notch in the sleeve and the eye in the male member, 45 spring jaws on opposite sides of said tongue, and arms projecting out of said peripheral notch, for the purpose set forth.
- 50 In testimony whereof I affix my signature in presence of two witnesses.

ISAAC GAUSE.
